UNITED STATES PATENT OFFICE.

THOMAS LAMBETH, OF RACHEL, NORTH CAROLINA.

WATER-WHEEL.

SPECIFICATION forming part of Letters Patent No. 794,030, dated July 4, 1905.

Application filed October 26, 1904. Serial No. 230,065.

To all whom it may concern:

Be it known that I, THOMAS LAMBETH, a citizen of the United States, and a resident of Rachel, in the county of Randolph and State of North Carolina, have invented a new and Improved Water-Wheel, of which the following is a full, clear, and exact description.

This invention relates to improvements in water-wheels of the undershot type, the object being to provide a simple and novel means for positively moving the blades outward to receive the water-pressure and moving them inward or into the wheel-body upon leaving the water, thus preventing back pressure.

15 I will describe a water-wheel embodying my invention and then point out the novel features in the appended claims.

Reference is to be had to the accompanying drawings, forming a part of this specification, 20 in which similar characters of reference indicate corresponding parts in all the figures.

Figure 1 is a sectional elevation of a water-wheel embodying my invention. Fig. 2 is a section on the line $x-x$ of Fig. 1. Fig. 3 is a section through the frame with the wheel removed. Fig. 4 is a plan. Fig. 5 is a section through one of the blades. Fig. 6 is a section on the line $y-y$ of Fig. 3, and Fig. 7 is a section through the regulating-gate.

30 Referring to the drawings, 1 designates the wheel-casing, with the lower portion of which the water-chute 2 communicates. Mounted in the casing is the water-wheel 3, which, as hereshown, consists of a practically solid block 35 having at suitable distances apart radial slots or openings 4, which extend from a point near the wheel-shaft 4^a and open outward, and in these slots the blades 5 are designed to slide. These blades 5 preferably consist of metal 40 plates and they are connected to the ends of the wheel by means of curved arms 6. The ends of the blades are bent at substantially right angles to the body, as indicated at 5^a, and these bent portions slide in recesses 5^b, formed in the ends of the wheel. These arms 45 have their ends mounted to swing in the ends of the wheel and travel in circular recesses 5^c, formed in the inner side of the casing, and carried by said arms adjacent to their 50 connection with the blades are rollers 7, which

extend into a recess, the upper portion of which is formed in the inner side of the casing, as indicated at 8, while the lower portion is formed by cam-plates 16, carried on plates 9, mounted to slide vertically on the casing. 55 The completed recess is substantially oval in form, and the wall thereof forms a cam against which the rollers 7 engage to force the blades outward when in a lowermost position, as indicated in Fig. 1. As the blades move loosely 60 in the slots the arms 6 will serve as braces.

Attached to the inner sides of the plates 9 are U-shaped metal plates 10, which form the inner wall of the cam-recesses. The plates 9 have beads 11, which engage in vertical channels 12, formed in the outer sides of the casing, as clearly indicated in Fig. 4, and the upper ends of these plates 9 are connected by a cross-plate 13 and firmly secured together by means of bolts 14. The lower ends of the plates 70 9 carry a gate 14^a, which is concaved on its upper side, and this gate is movable in an opening 15 in the lower portion of the casing. By moving the plates 9 upward it is obvious that the gate 14^a will be moved upward to reduce the outlet or opening through which water may pass to operate upon the blades, and by moving said parts upward the recess comprising the parts 8 and 16 will be reduced 75 in length, thus regulating the outward movement of the blades. Mounted to swing on the bottom wall of the chute 2 is a deflector-plate 17, the inner or free end of which engages with a strip 18 on the gate 14^a, and therefore this plate will be moved up and down with said 80 gate, so as to direct the water thereto. The plates 9 of the gate may be raised and lowered by any suitable means. I have here shown for this purpose the plates 9 as provided with racks 19, meshing with pinions 20, mounted 85 on arms 21, having angular shaft portions 22, with which a crank may be engaged.

In the operation as the water passes through the chute it will cause a pressure on the blade or blades that may be extended from the wheel, 95 and as the wheel rotates the cam-walls of the recesses 8 and 16 will cause an inward movement of the upwardly-moving blades and cause an outward movement of the lower blades. I have here shown the gate 14^a as detachably 100

connected to the side plates 9. The connecting devices consist of loop-bars 23, having swinging connection with the plates 9 and adapted to pass underneath the ends of the 5 gate.

Having thus described my invention, I claim as new and desire to secure by Letters Patent—

1. A water-wheel comprising a casing having openings in its side walls, plates mounted 10 to slide in the casing and having curved portions, the walls of said openings with the curved plates forming substantially oval tracks, a wheel mounted in the casing and having radial openings, blades movable in said openings, arms having swinging connection with the ends of the wheel and also having swinging connection with the inner ends of the blades, rollers on said arms for engaging the 15 walls of said tracks, and a chute leading to the lower portion of the wheel.

2. A water-wheel comprising a casing, a chute leading into the lower portion thereof, a wheel mounted in the casing, blades movable radially out of and into said wheel, adjustable means for causing such inward and outward movements, and a vertically-adjustable gate in the lower portion of the casing directly under the wheel.

3. A water-wheel comprising a casing, a chute communicating with the lower portion thereof, a wheel arranged in the casing, radially-movable blades carried by the wheel, adjustable means for causing inward and outward movements of the blades, a gate in the lower portion of the casing directly under the wheel and adjustable toward and from the

wheel, and a deflector-plate mounted to swing in the chute and operating with said gate.

4. A water-wheel comprising a casing, a chute communicating with the lower portion 40 thereof, the said casing being provided with openings in its side walls, the upper ends of said openings being of oval form, plates mounted to slide on the outer sides of the casing, U-shaped plates secured to the sliding plates 45 within the openings, a wheel mounted in the casing and having radial openings, blades mounted to slide in and out of said openings, arms having swinging connection with the ends of the wheel and having pivotal connection with said blades, rollers carried by the arms for engaging in said openings in the end walls of the casing, and a gate in the lower portion of the casing adjustable toward and from said wheel.

5. A water-wheel comprising a casing, a chute communicating with the lower portion thereof, said casing having an opening at the lower end, a gate adjustable in said opening 60 directly under the wheel and having a concaved upper side, a wheel mounted in the casing, blades carried by the wheel and movable radially into and out of the same, and adjustable mechanism for causing said inward and outward movements.

In testimony whereof I have signed my name to this specification in the presence of two subscribing witnesses.

THOMAS LAMBETH.
